UNITED STATES PATENT OFFICE.

EMMETT F. CAPLEY, OF ASPENHILL, TENNESSEE.

CLAMP FOR MAIL-CRANES.

SPECIFICATION forming part of Letters Patent No. 644,819, dated February 27, 1900.

Application filed June 26, 1899. Serial No. 721,878. (No model.)

To all whom it may concern:

Be it known that I, EMMETT F. CAPLEY, a citizen of the United States, and a resident of Aspenhill, in the county of Giles and State of Tennessee, have invented certain new and useful Improvements in Clamps for Mail-Cranes, of which the following is a specification.

The object of my invention is to provide a clamp which is adapted to securely attach a mail-pouch to a mail-crane and to hold the same in position to be engaged by the mail-collecting apparatus of a mail-car and at the same time to permit the said apparatus to readily disengage the mail sack or pouch from the clamp as the train passes the station where the crane is located and avoid all danger of tearing or injuring the pouch when detaching it from the crane.

To this end my invention consists in the peculiar construction and combination of devices, that will be more fully set forth hereinafter and particularly pointed out in the claims.

In the accompanying drawings, Figure 1 is a side elevation of one of my improved clamps. Fig. 2 is an elevation on a reduced scale, showing a mail-crane provided with a pair of my improved clamps in position for holding a mail-pouch.

A B represent the jaws of one of my improved mail-clamps, which jaws are pivoted together by a bolt or pin C in alined openings in ears or lugs a b, with which the jaws A B are respectively provided. The engaging ends of the jaws are globular in form, as at a' b', and the opposite ends of the said jaws are extended for a suitable distance beyond the pivot and shaped to form the handles or levers D. A stud, bolt, or pin E is fitted in an opening F near the engaging end of the jaw B, and a tension-bolt G is feathered or splined in a similar opening H near the engaging end of the jaw A and is provided at its outer extremity with a tension-nut I, which is provided with a handle or lever K, by means of which it may be readily turned. A coiled retractile spring L has its extremities attached to the inner ends of the stud E and tension-bolt F and serves to normally draw the jaws toward each other and keep their engaging ends in contact with each other, as will be readily understood, and by means of the tension bolt

and nut the tension of the said spring can be regulated at will. A bracket-arm M, which is adapted to be bolted to one of the arms of a mail-crane such as are now in common use and as shown in Fig. 2, has its outer end swiveled or pivoted in an opening N in the member B, a nut O and pin P being employed to retain the clamp on the said bracket, while permitting the clamp to swing freely thereon.

In the manufacture of my improved clamp I propose to make the same of iron, steel, or other suitable material, and the spring should preferably be made of brass to prevent rusting from exposure to the weather.

In operation two of my improved clamps are employed and are attached to the mail-crane, as shown in Fig. 2, the globular engaging ends of the jaws of the clamps being engaged with the rings x, with which the mail-pouch y is provided, as is usual. The clamps being supported one above the other at a suitable distance apart and permitted to play freely on the ends of the bracket-arms, the mail-pouch is held in position to be engaged by the collecting apparatus of a mail-car as the latter passes the station. The arm of the said mail-collecting apparatus will strike about the middle of the mail-pouch, and as the latter is supported at both extremities by the mail-clamps and the latter are free to play or oscillate on their pivots the mail-pouch will double upon the arm of the mail-collecting apparatus, and as the car moves the pouch will be pulled from the clamps, the rings at the extremities of the pouch slipping from between the globular ends of the jaws of the clamps, as will be readily understood.

By making the ends of the jaws globular in form all danger of the pouch becoming hung to the clamps will be avoided and there will be no probability of the pouch becoming torn while being detached from the crane. The tension-springs can be adjusted as may be necessary to hold the mail-pouch during the prevalence of high winds and at the same time permit the pouch to be readily detached from the crane by a passing mail-car.

Having thus described my invention, I claim—

1. The mail-pouch clamp, comprising the two members pivoted together, and having the jaws at one end with the globular engag-

ing extremities, the handles at the opposite ends of the members, the spring to normally keep the globular ends of the jaws in engagement with each other, and the bracket-arm, 5 to which one of the members is pivoted or swiveled, said bracket-arm being adapted to be bolted or otherwise secured to the arm of a mail-crane, substantially as described.

2. In a mail-pouch clamp, the combination 10 of the pivoted jaws A, B, having the engaging ends a' , b' , and the handles D, with the spring L, stud E and tension-bolt G, substantially as described.

3. The bracket-arm M, having the pin O, in 15 combination with the mail-pouch clamp com-

prising the pivoted jaws A, B, having the engaging ends a' , b' , the handles D, and the spring and tension devices, one of said jaws being pivoted on the pin O, as at N, substantially as described.

In testimony that I claim the foregoing I have hereunto attached my signature, at Aspenhill, Giles county, Tennessee, this 18th day of May, 1899, in the presence of two subscribing witnesses.

EMMETT F. CAPLEY.
